UNITED STATES PATENT OFFICE.

MELVIN HORSEY, OF CRISFIELD, MARYLAND.

ADVERTISING DEVICE.

1,352,368.

Specification of Letters Patent. Patented Sept. 7, 1920.

Application filed July 3, 1919. Serial No. 308,541.

To all whom it may concern:

Be it known that I, MELVIN HORSEY, a citizen of the United States, residing at Crisfield, in the county of Somerset and State of Maryland, have invented new and useful Improvements in Advertising Devices, of which the following is a specification.

This invention relates to advertising devices, and the principal object of the invention is to provide means for causing a pair of figures, representing a man and a woman, to move toward and away from each other, said figures being so arranged that their lips will contact as the figures come together so as to represent the figures as kissing.

Another object of the invention is to provide means, such as a spring motor, for intermittently raising one figure away from the other and permitting it to fall back by the action of gravity, assisted, when necessary or desirable, by a resilient member.

Still another object of the invention is to provide a transparent plate in front of the figures and a combined supporting and display casing at the rear of the plate and below the figures for supporting the device and containing the object or article to be displayed, which may be seen through the said plate.

The invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a front view of the device; Fig. 2 is a rear view with parts omitted; Fig. 3 is a longitudinal sectional view; Figs. 4 and 5 are detail views.

In these views 1 indicates a frame for the device which is arranged to receive a transparent plate 2. Upon this plate is placed the stationary part of the sign which may be formed of a sheet 3 formed of cardboard or the like. The upper part of this sheet is provided with an opening 3' for receiving the movable part of the sign. This movable part consists of a pair of members 4 and 5 which are pivoted to the sheet 3. This sheet 3 may be reinforced at the pivotal

points or wherever necessary. The sheet 3 is provided with an irregularly-shaped part 6 which extends into the lower part of the opening 3', and the lower parts of the members 4 and 5 engage the rear face of this part 6. The portions of the members 4 and 5 projecting above this part 6 are formed to represent the heads of a man and a woman. The member representing the woman is of less height than that representing the man, and the member representing the man carries the representation of the woman's arm as encircling his neck. The part 6 and the part of the plate 3 immediately below said part, carry the representation of a man's forearm with his hand holding his hat and with the arm appearing in front of the woman's neck so that the two figures, and the illustration below them, represent the woman as lying in the man's arms with her arm encircling his neck. The pivotal points of the two figures or members 4 and 5 are so arranged that gravity will cause the two figures to assume a position with their lips together in the act of kissing.

In order to insure the figures moving into this position and to assist the force of gravity, I may provide a spring or resilient member 7 which has one end connected to the member 4, which is the representation of the man, and its other end connected to a stationary part of the sheet 3 or its reinforcement. It will be seen that a part of the edge of the member 4 will bear against the edge of the member 5 so that the downward movement of the member 4 will be communicated to the member 5 if gravity should fail to move the said member 5. I may also place plates 8 on said members to act as weights to insure their movement by gravity. Plates 8' are located at the bottoms of said members which also act as weighting means and to strengthen the pivotal points. The plate 8' and the bottom of the member 4 is notched as at 8x.

The means for moving the figures upwardly away from each other consist of a wheel 9 driven from any suitable source of power such as the spring motor 10, and which carries the pins 11 which are adapted to strike the bottom of the figure 4, and the lower edge of the plate 8' to tilt said member 4 upwardly upon its pivot pin. As will be seen, the pins engage that part of the member which is adjacent the edge which is farthest from the pivotal point. Thus the pins will rock the member 4 upon

its pin and thus force the same upwardly and away from the member 5. The member 5 will also be given a slight upward movement toward the other member by reason of the fact that the two members are connected together by the string or cord 12. The wheel 9 revolves in a recess 13 formed in the reinforcement of the sheet 3.

The motor 10 may be carried by a cross piece 14 which forms part of the packing of the frame and which also helps to support the pivot pins of the two members. The shaft carrying the wheel 9 passes through this piece and the said wheel is on the inner face of said piece. This spring motor may also be made to actuate an alarm 15 and this actuating means may be so arranged that the alarm will ring every time the figures kiss.

20 A casing 16 is located at the rear of the frame 1 with its upper edge engaging the cross piece 14 and its lower edge forming a rest or support for holding the frame in upright position. I may provide a bottom 25 for said casing which is secured to the bottom piece of the frame and is suitably connected with the casing. One end of the casing may be arranged as a door to provide access to the same.

30 The lower part of the sheet 3 may be cut as shown in Fig. 1 to form a flap 18 which may be bent inwardly within the casing. In this way an opening is provided through which anything placed in the casing, may 35 be seen through the transparent front plate of the frame. The flap is pushed inwardly and acts as a cover for the article being displayed. The sheet 3 may contain any desired advertisements. A suitable backing 19 40 is used for holding the parts of the device in the frame and acting to hold the movable members against the glass.

It will thus be seen that when the spring motor is wound up the rotation of the wheel 45 9 will cause its pins to contact with the bottom edge of the member 4 to raise the same and thus cause the figures to move apart. Upon the continued rotation of the wheel, the pin will pass into the slot 8 so 50 that the figure 4 will swing downwardly under the action of gravity and as its edge strikes the edge of the other member this other member will also be rocked slightly so that the faces of the members will come 55 together and their lips contact thus representing the figures as kissing. The chin of the man and the nose of the woman are slightly curved inwardly so as to permit the man's chin to pass behind the woman's 60 chin and the woman's nose to pass behind the man's nose to permit their lips to contact. The figures will remain in this position until the next pin strikes the edge of the member 4 when the said members will 65 again move apart. Thus the movement of

the figures will attract the notice of persons walking along the street so that they will stop to watch the same and will thus notice the advertising matter on the sign and also the article displayed in the casing. 70

It is thought from the foregoing description that the advantages and novel features of my invention will be readily apparent.

I desire it to be understood that I may 75 make changes in the construction and in the combination and arrangement of the several parts, provided that such changes fall within the scope of the appended claims. 80

What I claim is:

1. A device of the class described comprising a pair of figures representing a man and a woman, supporting means upon which the figures are pivotally mounted in such a 85 manner that the figures will assume a position caused by gravity with their lips in contact, means engaging one of the figures for intermittently moving the figure away from the other figure and means for imparting a limited movement to the last mentioned figure by the movement of the first mentioned figure. 90

2. A device of the class described comprising a supporting frame, a pair of movable members pivotally mounted thereon, the outer face of said frame and the exposed portions of said members being illustrated to represent a man and a woman embracing each other and means for moving 95 the members toward and away from each other, said members being so arranged that their lips will contact with each other as they approach one another, said actuating means including a pin wheel engaging the 100 lower part of one member, spring means for holding the member against the pins of said wheel and a flexible member connecting the two members together. 105

3. A device of the class described comprising a supporting frame, a pair of figures pivotally supported thereon and representing a man and a woman, means for moving the figures toward and away from each other and a display casing at the lower part of 110 the frame and acting as a supporting means therefor. 115

4. A device of the class described comprising a supporting frame, a pair of figures pivotally mounted thereon and representing a man and a woman, means for moving the figures toward and away from each other, said figures being so arranged that their lips will contact as the figures approach each other, a spring motor for actuating said means and an alarm actuated by the motor at the moment the figures come together. 120 125

In testimony whereof I affix my signature.
MELVIN HORSEY.
